PORTABLE TWO-WAY RADIO APPARATUS OR SIMILAR ARTICLE

Richard Toth and Donald Krumin, Fort Lauderdale, Fla.,
assignors to Motorola, Inc., Schaumburg, Ill.

Filed Aug. 6, 1975, Ser. No. 602,334

Term of patent 14 years

Int. Cl. D14—03

U.S. Cl. D26—14 K

FIG. 1 is a front perspective of a two-way radio apparatus or similar article showing our new design;

FIG. 2 is a rear elevation thereof; and

FIG. 3 is a side elevation as seen from the side opposite FIG. 1.

We claim:

The ornamental design for a portable two-way radio apparatus or similar article, substantially as shown.
